UNITED STATES PATENT OFFICE.

AUGUST BOSTROEM, OF NEW YORK, N. Y., ASSIGNOR TO SAMUEL ROBERT SCHWARTZ,
OF NEW YORK, N. Y.

DESIGN FOR A PORTABLE LAMP BASE.

61,361.

Specification for Design.

Patented Aug. 15, 1922.

Application filed November 3, 1921. Serial No. 512,639. Term of patent 7 years.

To all whom it may concern:

Be it known that I, AUGUST BOSTROEM, a citizen of the United States of America, residing at New York, in the county of Bronx and State of New York, have invented a new, original, and ornamental Design for a Portable Lamp Base, of which the following is a specification, reference being had to the accompanying drawing, forming part thereof.

The figure is a perspective view of the portable lamp base showing my new design. It is shown in connection with a standard type of electric desk lamp and all parts ex-

cept the subject of my invention are indicated in dotted lines.

I claim:

The ornamental design for a portable lamp base, as shown.

In testimony whereof, I have signed my name to this specification in the presence of two subscribing witnesses, this twenty-sixth day of October, 1921.

AUGUST BOSTROEM.
